UNITED STATES PATENT OFFICE.

THOMAS FREDERICK SPACKMAN, OF CHICAGO, ILLINOIS, ASSIGNOR TO STEWART-WARNER SPEEDOMETER CORPORATION, OF CHICAGO, ILLINOIS, A CORPORATION OF VIRGINIA.

VACUUM-OPERATED LIQUID-LIFTING DEVICE.

Application filed July 16, 1927. Serial No. 206,289.

The purpose of this invention is to provide an improved construction for lifting liquid by suction induced by air flow through a Venturi-shaped passage, particularly adapted for such purpose as lifting fuel from a low source for supplying an internal combustion engine carburetor by gravity. It consists in the elements and features of construction shown and described as indicated in the claims.

In the drawings:

Figure 1 is a top plan view of a fuel receptacle equipped with a device embodying this invention for filling the receptacle with the liquid fluid derived from a lower source by suction.

Figure 2 is a vertical section of the same at the line 2—2 on Figure 1.

Figure 3 is a section at the line 3—3 on Figure 2.

Figure 4 is a top plan view of a modified form of the device.

Figure 5 is a section at the line 5—5 on Figure 4.

Figure 6 is an axial section of the suction-inducing Venturi member of the forms shown in Figures 4 and 5.

The structure shown in the drawings is formed in detail for mounting on a motor vehicle or the motor thereof for supplying the engine with fuel from a main supply tank which may be located at the rear of the vehicle and at a substantially lower level than the carburetor to which the fuel is supplied by gravity flow from the receptacle indicated at A through which the fuel is led from a low level source, not shown, by a pipe, B, which is connected for discharge through the cap of the receptacle as seen at b, and from which the fuel flows to the carburetor, not shown, by pipe, C.

As illustrated, the receptacle, A, comprises two chambers A¹ and A²—A¹ being the receiving chamber in which a partial vacuum is produced in the operation of the structure when connected as designed for the service indicated. The chamber, A², is an accumulating chamber, or reservoir into which the fuel lifted by suction into the chamber, A¹, is discharged by gravity or under certain conditions as hereinafter explained, by gravity plus super-atmospheric pressure, past the valve, D, which is opened in the direction of such discharge by gravity or gravity flow of the liquid, or by the pressure

indicated, the pipe, C, which leads to the carburetor being connected at the lower part of said chamber, A².

The receptacle, A, is closed at the top by a top plate or cap, E, to which the pipe, B, is connected for discharge of fuel into the chamber, A¹, as mentioned. A transversely extending exteriorly protruding boss, 20, with which the cap plate, E, is provided has extending through its entire length a Venturi-shaped passage, 21, 22, 23, of which the part, 21, constitutes the entrance part of the venturi and 23 is the discharge or delivery part, the Venturi construction being seen at 22. A slot, 25, which is cut transversely of the Venturi passage from the under side of the top, E, constitutes a communication between the chamber, A¹, and the Venturi passage. As shown and for the specific purpose hereinafter indicated, this slot, 25, extends entirely across the Venturi passage at a position a little distance from the Venturi constriction toward the entrance end of the Venturi passage. F is a nozzle exteriorly tapered over a short distance toward its discharge end, and diametered back of the tapered part for fitting and being held snugly in the entrance part, 21, of the Venturi passage antecedent to the slot, 25. Desirably the taper of the discharge end portion of the nozzle, F, corresponds approximately to the taper of that part of the Venturi passage in which said tapered part of the nozzle stands, the nozzle being enough less in diameter than said tapered part of the Venturi passage to leave an annular space 26 in the Venturi passage all around the tapered nozzle terminal.

With the construction described it may be understood that upon air flow being caused through the Venturi passage, the lowering of pressure which will result in the vicinity of the Venturi constriction will cause relatively rapid air inflow through the slot, 25, tending to produce a partial vacuum in the chamber A¹; and that upon such air flow through the venturi being arrested or cut off at any one point in the length of the Venturi passage, at either side of the slot, 25, or in the pipe leading to the Venturi passage from either direction, access being uninterrupted at the other side of the slot, flow will take place through the annular space, 26, and the slot in the chamber, A¹, tending to destroy the partial vacuum.

created therein by the previous flow through the Venturi passage. For interrupting and cutting off the air flow through the Venturi air passage at a selected point as indicated, 5 a shut-off valve is provided in a bore, 30, which leads from the under side of the top, E, transversely of the Venturi passage at the opposite side of the constriction, 22, from the slot, 25, and as wide as the diameter 10 of said passage at that point; and fitting slidingly in said slot there is provided a slide valve, 32, having a portion, hereinafter referred to as the stem, 32^a, extending down into the chamber, A¹, for which stem there 15 is provided toward its lower end, most conveniently at the vicinity of the discharge port, 19, a bearing, 34, for the further guidance of said stem, 32^a, in the sliding movement of the valve to open and close the 20 Venturi passage. On this stem, 32^a, there is slidably mounted between an upper stop, 33, and a lower stop, 34, a float, 35, which at a predetermined high level of the liquid in the chamber, A¹, encounters the upper stop, 25 33, and as the liquid continues to rise, lifts the valve, 32, to position closing the Venturi passage and stopping the air flow therethrough, thereby interrupting the action for withdrawing air from the chamber, A¹, as 30 by suction, which while it was in progress, produced a condition of partial vacuum in the chamber, A¹; and thereupon the air which was entering at the entrance end of the Venturi passage, continuing to enter 35 either under atmospheric pressure, when the air flow was produced by suction, (or under super-atmospheric pressure, which while the valve was open produced the air flow through the Venturi passage,) passing by 40 the end of the nozzle, F, finds its way back around the nozzle tip and by way of the slot, 25, passes into the chamber, A¹, relieving the partial vacuum which was produced therein by the air flow through the venturi; and 45 when the partial vacuum has by this means been relieved to a degree at which the liquid can be delivered by gravity past the valve, D, the evacuation of the chamber of liquid will 50 occur by gravity; and the float, 35, being lowered as the level of the liquid falls, eventually encounters the lower stop, 36, and by its weight retracts downwardly the stem, 32^a, and valve, 32, opening the Venturi passage for air flow therethrough which will 55 cause the previous action for inducing suction to be repeated through the cycle of said action above described.

It will be evident that it is immaterial for 60 the purpose of the vacuum-producing action above described whether the air flow through the Venturi passage is caused by super-atmospheric pressure at the entrance end; or by sub-atmospheric pressure at the discharge end; and accordingly, when the device is employed for supplying fuel from a

low source of the carburetor of an internal combustion engine, the operating connection may consist of connection at the discharge end of the Venturi passage to the intake manifold of the engine, leaving the entrance 70 end of the venturi open to atmosphere. Or the operating connection may consist of connection of the entrance end to the engine exhaust passage; and the opposite end in such case being the discharge end, may be 75 open to the atmosphere, or connected to the intake manifold.

When the air flow through the venturi is produced by suction, as when the structure is employed for fuel lifting by connection 80 of the Venturi passage with the intake manifold of an engine served as above described, the condition of vacuum in the Venturi passage beyond the valve, 32, may serve to hold the valve up until the float has fallen to the 85 stop, 34, as above described. But when the air flow is produced by super-atmospheric pressure, as by connection with the engine exhaust for blowing through the Venturi passage, the suction means of upholding the 90 valve being absent, any suitable means may be substituted to prevent the valve from dropping until it is withdrawn by the float. A simple means for the purpose may consist in making the stem, 32, hollow for lightness 95 and making the stop, 36, of cork or the like of suitable size to balance by its buoyancy the weight of the stem.

This expedient is not without value in the case of the suction-produced air flow to 100 supplement the upholding power of the suction which may not always be adequate to uphold the valve when the latter has become loose fitting in the slot in which it slides for closing the Venturi air passage, so that air leakage past it, which would not otherwise interfere with the operation of the structure, would defeat the upholding 105 power of the suction.

In the drawings, Figure 5 illustrates a 110 modification consisting in employing a "snap action" for producing quick and substantially instantaneous movement of the Venturi passage controlling valve both in opening and closing. For this purpose 115 there are pivoted at 100 to a lug, 101, which projects downwardly from the under face of the cap, EE, two levers, 102 and 103, extending in opposite directions from their pivot-in-common at their medial position 120 substantially horizontally across the chamber, A¹, and having their opposite free ends provided with cross pins, 104—104, whose corresponding ends at both sides of the 125 levers are connected by stretched springs, 105—105; so that as the levers are swung to carry the pins, 104, past a position of alignment with the pivot-in-common of the levers, the re-action of the springs tends to snap the levers further in the direction in 130

which they are moving as soon as the pins 104 pass said position of alignment. The valve stem, 32, extends through an aperture, 110, in the lever, 102, and has above and below that lever at a short distance apart, stops, 111-112; and the opposite end of the lever 103, is connected by a link, 107, with a third lever, 108, pivoted to a lug, 109, extended down from the cap, EE, 10 said third lever extending at a short distance below the levers, 102 and 103, and a guide stem, 115, for the float, 35, is pivotally connected to said third lever at the opposite side of the link, 107, from the fulcrum of 15 said lever so that the float rising along the stem to encounter with a stop, 116, on said stem above the float, swings said third lever up and through the link, 107, and moves the free end of the lever, 103, upward, even- 20 tually carrying the point of attachment of the springs past position of alignment of the opposite end connection of the spring with the pivot-in-common causing the re-action of the springs to snap the levers up 25 as above described, bringing the lever, 102, in contact with the upper stop, 111, on the valve stem, 32, and thrusting the valve to closed position. Similarly upon descent of 30 the float resulting from lowering the level of the liquid and its encounter with the lower stop, 117, on the float guide stem, the latter is pulled downward, producing lever action to the contrary of that above described, causing the downward snap action 35 of the levers by which the lever, 102, is moved into encounter with the lower stop, 112, on the valve stem and the valve is thereby retracted to open position.

In the form shown in Figures 4 and 5, the 40 suction-inducing Venturi passage for air flow is desirably formed in a fitting, J, shown in Figure 6, which is drive fitted in a horizontal bore formed through the cap plate, EE, as may be understood from Figure 5, said fitting, J, being forced into place in the cap plate before forming in it a cross port at, γ , which will be formed by drilling after the fitting, J, is in place to ensure registration with the previously existing port, 50 30 γ , in the cap plate, EE.

To prevent the levers, 104 and 105, being snapped down too far and pulling the valve, 132, entirely out of its seat and guideway in the top, E, there is provided a stop rod, 40, suspended from the top, E, at a point above the lever, 105, which has a hole, 105 α , through which the stop rod, 40, extends, said rod having a head, 41, at its lower end, which head is positioned by the length of 60 the rod properly for stopping the down swing of the lever, 105. It will be understood that the top, E, is bored for the upper end of the stop rod, 40, and counterbored to afford access to the end of the stop rod after 65 it is inserted up through the lever, 105, and

through said bore. In order to form upon said upper end of the stop rod a head by which it may be suspended from the top as mentioned, the upper end of the counterbore is threaded to receive a closure plug, 70 after the parts have been assembled.

When this construction is employed in the usual relation of a vacuum tank to a low level fuel supply to the engine and connected for operation by pressure, as by connection of the left-hand end of the venturi with the engine exhaust, in which case super-atmospheric pressure will exist in the vacuum chamber when it is discharging into the lower or outer chamber referred to as the reservoir, it will be desirable to obviate the liability to overflow of the outer chamber when the quantity of fuel pumped exceeds the engine requirements and consumption, either to omit or close the usual atmosphere port shown at 40, 41, or to provide access for the super-atmospheric pressure from the vacuum chamber to the outer chamber; and this latter expedient is shown in Figure 2 consisting of a port, 43, of communication between the two chambers located at the upper part above the float-controlled high liquid level of the vacuum chamber with a gravity operated check valve, 42, opening for flow from the inner to the outer chamber. The pressure being thus equalized between the two chambers when that in the inner chamber is atmospheric and flow only occurring when it is sub-atmospheric, the liquid can rise no higher in the outer chamber than the controlled high liquid level of the inner chamber. 100

I claim:—

1. In combination with a receptacle for liquid, a fitting mounted on the receptacle 105 having extending through it a Venturi-shaped passage adapted for connection at one end with means for inducing air flow through the passage, and having between the entrance end and the Venturi constriction a lateral communication with the liquid chamber of the receptacle, a valve positioned for closing the Venturi passage without closing its communication with the liquid chamber, and means controlled by the liquid content of the chamber for opening and closing said valve. 110

2. In the construction defined in claim 1, the air flow inducing means being in connection with a source of suction and the valve being located between the Venturi end which is connected with such source of suction and the Venturi constriction. 120

3. In the construction defined in claim 1, the air flow inducing means being in connection with a source of suction, and the valve being located at the side of the Venturi constriction toward the suction-connected end of the venturi. 125

4. In the construction defined in claim 1, 130

the air flow inducing means being in connection with a source of suction, and the valve being located between the suction source and the Venturi communication with the liquid chamber.

5. In the construction defined in claim 1, the receptacle having connection for liquid flow from a liquid source at a lower level, and a liquid outlet at the lower part, the valve controlling said outlet adapted to be opened by gravity flow of the liquid, the means for operating the valve in the Venturi passage being a float in the chamber, and the valve stem extending into the chamber for engagement by the float for closing the valve at a predetermined high level of the liquid and for opening the valve at a predetermined low level of the liquid.

6. In combination with a receptacle for liquid, a fitting mounted on the receptacle having extending through it a Venturi-shaped passage adapted for connection at one end with means for inducing air flow through the passage, and having between the entrance end and the Venturi constriction a communication with the liquid chamber of the receptacle, a valve positioned for closing the Venturi passage without closing its communication with the liquid chamber, said valve having its stem extending into the liquid chamber, a float in said chamber positioned and guided for encounter with the valve stem for closing the valve at a predetermined high level of liquid in the chamber, said stem having also means for encounter with the float in a direction for opening the valve at a predetermined low level of the liquid.

7. In a construction of the character indicated, in combination with a chamber connected for receiving liquid from a lower

source, means for inducing partial vacuum in said chamber; a valve which controls the vacuum-inducing means, said means being adapted for venting the chamber by the admission of pressure to overcome the vacuum when said valve is positioned for interrupting the vacuum-inducing action; means operated by change of liquid level in the chamber for actuating said valve to cause such interruption at a predetermined high liquid level, and to terminate the interruption at a predetermined low liquid level, a part in the connection for actuating the valve being extended in the liquid in the chamber at the predetermined low level of said liquid and being formed and equipped at the part which is submerged at said low liquid level for being buoyed by the liquid to a substantially balanced condition subject to being actuated in either direction by the valve-actuating means.

8. A device of the character indicated, comprising in combination with a fuel receptacle a fitting mounted on the receptacle having a Venturi shaped passage adapted for connection at its opposite ends with regions of differing fluid pressure, said fitting having a slot transverse to the Venturi passage opening thereinto and also into the liquid chamber of the receptacle; and a tapered nozzle mounted in the Venturi passage at the side of the Venturi constriction toward the entrance end of said passage protruding its tapered end across said slot spaced from the wall of the passage and terminating for discharge through the constriction.

In testimony whereof, I have hereunto set my hand at Chicago, Illinois, this 8th day of July, 1927.

THOMAS FREDERICK SPACKMAN.
